UNITED STATES PATENT OFFICE.

WALTER G. BRIDGE, OF NEWTON, MASSACHUSETTS, ASSIGNOR TO CHARLES E. PARK-HURST, OF SOMERVILLE, MASSACHUSETTS.

ARTICULATOR.

Application filed January 25, 1926. Serial No. 83,468.

This invention relates to the class of devices known as dental articulators. These devices as generally made are designed to hold dentures for the proper shaping of 5 false teeth, inlays, crown and bridge work, and the like, and usually have a hinged support for at least one of the dentures to enable them to be moved in relation to each other in order to simulate the conditions of 10 mandibular movement. Being provided with hinge joints such articulators have had the disadvantage that they failed to reproduce fully the grinding action of the human masticatory apparatus as ordinarily taking 15 place.

It is a well known fact that the mechanism of the human masticatory system is so arranged that the teeth are not only brought into abutting relation but also into a grinding 20 relation, tending to have a limited forward and backward as well as a sidewise motion. The chief object of the present invention is the provision of a dental articulator in which the mandibular motions and 25 the occlusal relations of the human jaw may be accurately simulated to enable dentures to be produced which will be more satisfactory in use and will need substantially no reshaping or trimming after they have been 30 fitted into the mouth of the patient. With this end in view the present invention provides an articulator not only enabling pivotal movement of the dentures in relation to each other but independent movement of 35 each end of the pivotal axis along a predetermined path which may itself be moved to various adjusted positions; also providing means whereby a relative sidewise movement may be imparted to the dentures when 40 supported upon the articulator. A further object of the invention is the provision of an articulator of this type which may be inexpensive to manufacture, and in which the oppositely disposed denture supports 45 may be readily disassembled to facilitate the fitting of the dentures thereto.

Fig. 1 is a plan view of the dental articulator;

Fig. 2 is a vertical cross section showing 50 the articulator in operative position;

Fig. 3 is a section on line 3—3 of Fig. 2; and Fig. 4 is an elevational view of the articulator.

An articulator made in accordance with 55 the principles of this invention may be

formed of a wide variety of materials assembled in accordance with different designs, but wire, preferably of semi-circular cross section, constitutes advantageous material for forming the framework of the 60 articulator, such material being utilized in the embodiment of the preferred form of my invention shown in the accompanying drawings.

In this embodiment the supporting frame 65 1 is formed of two substantially similar members 3 and 4 which are constructed of a somewhat ductile wire of semi-circular cross section. Frame members 3 and 4 are joined at their lower ends by the juxtaposed extensions 6 and 7, the flat faces of which are held in light frictional engagement by a sleeve 5, thus permitting the movement of 70 these members in relation to each other and their separation when desired.

Extensions 6 and 7 are formed by the 75 ends of the wires which comprise frame members 3 and 4 respectively, and the main portion of each of these members consists of an upwardly extending arm 8 formed by 80 bending a portion of the wire back upon itself with a binding ring 18 holding the wire sections in abutting relation near the base of the frame. The supporting projections 19, formed by the wire ends adjacent 85 extensions 6 and 7, may project approximately at right angles to the latter and to the arms 8. In each of the arms 8 the wire sections slightly diverge from the ring 18 towards a substantially circular loop 9 at 90 the upper part of the arm 8. A supporting block 10, with a peripheral groove 12 engaging the loop 9, is located at the upper end of each of the upright portions 8. A thumb nut 11 is threaded upon the diverging 95 portions of the wire below the loop 9, being provided with a flared portion engaging the diverging wire sections adjacent its upper face. Tightening of the nut 11 causes the loop 9 to grip the block 10 firmly in position, while loosening of the nut 11 enables 100 the diverging portions of the wire to spring slightly apart, thus permitting the turning of block 10 within loop 9.

A radial slot 13 is provided in each of 105 the blocks 10 and is designed to receive the pintle portion 24 of a support 16 which may be of any suitable form to engage bite block 22 carrying the upper denture. Such a frame member 16 may be of substantially 110

A-shape, as shown, with the triangular portion 17 at the apex of the member designed to be embedded in the block 22 or secured thereto in any desired manner. Support 16 5 may readily be made of wire of semi-circular cross section, such as used for frame members 3 and 4, with each of the pintle portions 24 formed by fusing a portion of this wire which is bent back upon itself into 10 an integral cylindrical projection with its inner end defined by shoulder 25.

Pintles 24 engage in the slots 13 with a fairly tight sliding fit and the rotation of the blocks 10 within the loop 9 is designed to 15 vary the location of the slots to suit individual conditions as indicated for example in full and dotted lines in Fig. 2. Adjoining the shoulders 25 are the annular washers 26 having convex surfaces adjoining the 20 slots 13 which have their edges slightly beveled as indicated more particularly at 14 in the cross sectional view of Fig. 3. The beveled edges of the slots and the curved washers are adapted to cooperate to permit 25 movement of the pintles 24 in relation to the slots without any tendency to bind and with the minimum of frictional resistance.

The operation of my improved articulator is substantially as follows: Blocks or models 30 22 and 23 having been prepared with dentures properly located thereon, frame members 3 and 4 are separated from each other sufficiently to permit the withdrawal of 35 pintles 24 from slots 13. The upper block 22 may then be fitted to the support 16 in any suitable way as by adding a layer of soft plaster of Paris to its upper surface in which the support 16 may be embedded. Support 16 is then re-assembled with 40 frame members 3 and 4 which are spaced at a distance apart to provide a clearance between the washers 26 and the blocks 10 if desired. The lower block 23 is then secured to the projections 19 at the base of the device 45 preferably by having these arms inserted in the block at an angle, as shown in Fig. 2. If necessary blocks 10 are adjusted to whatever position may be desirable in order to dispose radial slots 13 at the proper angle 50 to suit the individual case. It is thus evident that blocks 22 and 23 may be moved in relation to each other not only about the axis defined by the pivot members, but along the predetermined paths determined by the 55 adjusted location of slots 13, as well as in accordance with the transverse movement permitted by an endwise motion of the pintle members, so that a relative movement in practically any desired direction can take 60 place between the abutting dentures and movement along the occlusal curve may be closely simulated, thus enabling dentures to be produced under conditions closely resembling those normally found in the human 65 mouth. In certain cases the ductility of the

wire will enable the relative location of parts of the articulator to be varied, for example the width of the support 16 may easily be altered within reasonable limits by bending its apex and thus the width of the 70 entire device may be changed.

I claim:

1. A dental articulator consisting of pivoted denture supports, one of said supports being formed of wire of semi-circular cross 75 section, portions of which are bent back upon themselves and fused into cylindrical pintles pivotally to engage the other denture support.

2. A dental articulator consisting of pivoted denture supports, one of said supports being formed of wire or semi-circular cross section, portions of which are bent back upon themselves and have their flat surfaces secured in abutting relation by clips, the 80 ends of these portions being fused into cylindrical pintles of reduced cross section provided with shoulders at their juncture with the abutting wire portions engaged by the 85 clips.

3. A dental articulator having a frame connecting a pair of denture supports, said frame consisting of two parts adapted to be held in normal engagement by one of the denture models which is detachably mounted 95 thereon.

4. A dental articulator having a frame connecting a pair of denture supports, said frame consisting of two parts held in normal engagement pivotally to support a denture support and being separable to permit the disengaging of the denture support, said parts being adapted to be held in normal engaging position by a denture model secured thereto and being releasable from 100 said position by the detachment of said model.

5. A dental articulator having a frame connecting a pair of denture supports, said frame consisting of two parts each having 110 a portion of substantially semi-circular cross-section normally held in engagement with a similar portion of the other part by means of a sleeve element having a light frictional engagement with said portions, said parts in 115 their normal position being adapted to have a denture support pivotally connected thereto and being separable by relative longitudinal sliding of the semi-circular portions in the sleeve to permit detachment of 120 said support, said frames being adapted to be held in their normal position by a denture model secured thereon, and being releasable from said position by the removal of said model.

6. A dental articulator comprising a pair of denture supports pivotally connected to each other by means comprising pintles engageable in slots in blocks, said pintles being provided with shoulders adjoining the slots, 130

and washers having convex outer surfaces disposed upon said pintles between the shoulders and blocks being adapted to engage the slots and to permit free relative 5 movement of the pintles in relation to the slots.

7. A dental articulator comprising a pair of denture supports pivotally connected to each other by means comprising pintles in 10 slidable engagement with slotted members, said pintles being provided with washers having convex surfaces adjoining the slots and said slots having beveled edges adjoining said washers, relative engagement of the 15 concave and beveled surfaces being designed to permit free sliding and pivoting between the pintles and slotted members.

8. A dental articulator having a pair of denture supports pivotally connected to each 20 other by means comprising a semi-circular resilient wire formed into a substantially circular loop with its flat surface engaging a circular groove in a block within the loop, screw-threaded means in adjustable engagement 25 with a portion of the wire adjacent the loop and adapted to draw the loop into firm gripping relation in the block or to permit the loose engagement of the loop with the block.

30 9. A dental articulator having a pair of denture supports pivotally connected to each other by means comprising a semi-circular

resilient wire formed into a substantially circular loop with its flat surface engaging a circular groove in a block within the loop, 35 portions of the wire adjoining the loop being slightly separated and inclined towards each other so that the flat surfaces thereof are in abutment at a distance from the loop, the inclined portions of the wire being threaded 40 and engaging an internally threaded member adapted to draw the loop into tight gripping relation with the block.

10. A dental articulator having a pair of denture supports pivotally connected to each 45 other by means comprising wire elements formed into substantially circular loops engaging circular grooves in blocks within the loops, portions of the wire adjacent the loops being slightly separated and inclined towards 50 each other so that their surfaces are in substantially abutting relation at a distance from the loop, each of the inclined wire portions being provided with threads upon its surface which is spaced away from the adjoining inclined wire portion and an internally threaded member engaging these 55 threaded wire portions and being adapted to draw each loop into tight gripping relation with the block.

Signed by me at Boston, Massachusetts, this sixteenth day of January, 1926.

WALTER G. BRIDGE.
